[57] CLAIM

The ornamental design for a golf tool collectors display rack, as shown and described.

DESCRIPTION

FIG. 1 is a front perspective view taken from the left end of a golf tool collectors display rack showing my new design;

FIG. 2 is a front elevation view thereof, on a reduced scale;

FIG. 3 is a rear elevation view of FIG. 2;

FIG. 4 is a left end elevation view thereof, the right end elevation view being a mirror image of the left end elevation view shown;

FIG. 5 is a top plan view thereof;

FIG. 6 is a bottom plan view thereof;

FIG. 7 is a top plan view thereof, with part of the center portion shown cut away for clarity of illustration; and,

FIG. 8 is front upward looking perspective view taken from the bottom lower right.

The broken line representation of golf tools in FIG. 1 is for illustrative purposes only and forms no part of the claimed design.
